(57) **CLAIM**

We claim, the ornamental design for a housing for an electronic device, as shown and described.

DESCRIPTION

FIG. 1 is a perspective view of a housing for an electronic device showing my present design; FIG. 2 is a front view thereof;

FIG. 3 is a rear view thereof;

FIG. 4 is a left view thereof;

FIG. 5 is a right view thereof;

FIG. 6 is a top plan view thereof; and,

FIG. 7 is a bottom plan view.

The dot-dash broken line represents a boundary of the claimed design. The dash-dash broken lines depict unclaimed environment. The broken lines form no part of the claimed design.
